DESIGN FOR AN OYSTER PLATE

Albert W. Dixon, Sarasota, Fla.

Application December 30, 1938, Serial No. 82,086

Term of patent 3½ years

To all whom it may concern:

Be it known that I, Albert W. Dixon, a citizen of the United States, residing at Sarasota, in the county of Sarasota and State of Florida, have invented a new, original, and ornamental Design for an Oyster Plate, of which the following is a specification, reference being had to the accompanying drawing, forming part thereof.

Figure 1 is a top plan view of an oyster plate, showing my design.

Figure 2 is a side elevational view.

Figure 3 is a sectional view taken on the line 3—3 of Figure 1.

I claim:

The ornamental design for an oyster plate, as shown.

ALBERT W. DIXON.
